Specification for Design. Patented Apr. 18, 1922.

Application filed October 17, 1921. Serial No. 508,385. Term of patent 3½ years.

To all whom it may concern:

Be it known that I, CHARLES MINOFF, a citizen of the United States, residing at Brooklyn, in the county of Kings and State of New York, have invented a new, original, and ornamental Design for a Paper Weight, of which the following is a specification.

This application has reference to a new, original and ornamental design for a paper weight, as shown in the accompanying drawing, in which,

Figure 1 is a view in perspective of the paper weight.

Figure 2 is a view thereof in elevation viewing the same from the side opposite that shown in Figure 1.

Figure 3 is a view of the paper weight in top plan.

Having thus described my design, what I claim as new, and desire to secure by United States Design Letters Patent is:

The ornamental design for a paper weight as shown.

In testimony whereof I affix my signature.
